UNITED STATES PATENT OFFICE.

RUDOLF OCHSCHIM, OF BERLIN, GERMANY.

GRINDING AND POLISHING MACHINE.

1,088,922.

Specification of Letters Patent. Patented Mar. 8, 1914.

Application filed March 7, 1913. Serial No. 752,765.

To all whom it may concern:

Be it known that I, RUDOLF OCHSCHIM, a citizen of the German Empire, and residing at Berlin, Germany, have invented certain new and useful Improvements in Grinding and Polishing Machines, of which the following is a specification.

The present invention relates to machines for grinding or sand-papering and polishing wood, marble and the like.

My invention likewise relates to machines wherein a slow progressive forward movement and a rotatory movement are imparted to the grinding or polishing pad.

15 The subject-matter of the invention differs from known machines in that on the one hand the pad is given, in addition to these two movements, a simultaneous centrifugal movement by means of a crank and 20 allowed free movement about the crank-pin by forming the latter as a ball-joint. In addition, the machine is so arranged that a rapid to-and-fro motion can also be imparted to the pad. For this purpose the shaft 25 for causing the slow progressive movement is axially displaced by means of suitable driving mechanism, *e. g.*, a crank or an auxiliary shaft having a right and left handed thread turning back on each other. In order 30 that the grinding or polishing head shall not share the rotary motion resulting from its being driven by its own crank but be guided parallel over the workpiece, the head is linked to a second crank which is 35 driven at the same speed as the main crank.

When all the motions provided in the machine are in gear, this machine enables the grinding or polishing pad to execute on the workpiece a resultant motion which exactly 40 corresponds to the 8-like motion given by hand, so that hand-polishing is exactly imitated. As a rule this motion is necessary only when polishing. When grinding the rapid reciprocatory motion of the head can 45 be thrown out of gear. The movements are of course in the form not precisely of figure 8's, but are loops similar to this figure which are staggered somewhat relatively to one another. The resultant movements of the 50 pad can be varied by adjusting the speeds of the driving mechanisms for the various movements.

One illustrative embodiment of my invention is represented by way of example in the 55 accompanying drawings, wherein:

Figures 1, 2 and 3 are front elevation, end

elevation, and top plan view respectively, showing a preferred form of my machine; Figs. 4 and 5 are front and end elevation, respectively, partly in section, enlarged, showing the grinding or polishing head together with its bearings and guides; Figs. 6 and 7 are front elevation and plan, respectively, enlarged, showing the device for obtaining a rapid to-and-fro movement of the grinding or polishing head, and Fig. 8 shows a detail of the latter device, and Fig. 9 is an elevation as seen from the inside of the machine showing the mechanism for raising and lowering the work-table.

Referring to the drawings, in the upper part of the two end walls *a*, *a* of the frame is journaled the shaft *b* which has a longitudinal groove and is driven by a belt-pulley *b'*. Below and somewhat behind the shaft *b* is a second shaft *c* likewise journaled in the walls *a*, *a*; this shaft *c* can be displaced axially in its bearings *c'*, and has a screw thread between the walls *a*, *a*. The shaft or spindle *c* has at one end a groove *f* which is used for keying thereto two pulleys *d* and *e* for an open and a crossed belt, so that the spindle *c* is rotated right or left handedly according to which belt is thrown over from the middle loose pulley *f*. The other end of the spindle *c* carries a head *g* which embraces an intermediate shaft *h* and is guided to slide on a rail *i* of the bracket *i* (Figs. 6-8). The shaft *h* is continuously rotated by means of a belt-pulley *h'* and has a right and left-handed thread, returning in itself into which a pin *k*, rotatable in the head *g*, enters. This pin has a U-like lug *k'* which fits into the thread in the shaft *h* and is of such a length that it can pass the crossings of the right and left handed threads, without encountering obstruction. A set-screw *l* enters into a groove *l'* of the pin *k* and prevents this pin from being unintentionally disengaged from the thread in the shaft *h*.

When the shaft *h* is driven by its belt-pulley *h'* the thread in the shaft *h* imparts to the head *g* and therefore to the spindle *c* a reciprocatory motion. The spindle *c* can also be rotated in the one direction or the other by means of its belt-pulleys *d* and *e*, because though it is not longitudinally displaceable in the head *g*, it is free to rotate therein. In addition to the two walls *a*, *a* are connected together by a front and a rear frame, *m*, *m'*, respectively, they are

joined together by two rails *n* on which runs a carriage *o* having four wheels *o'* both above and below said rails (Figs. 4 and 5). The bearings of the wheels *o'* are vertically displaceable in the frame of the carriage and can be so fixedly adjusted by screws *p* that the carriage *o* is exactly prismatically guided on the rails *n*. Journaled in the carriage *o* is a bevel-gear *q* whose key *q'* enters into the groove of the shaft *b* and can therefore be readily longitudinally displaced with the carriage, but is rotated by the shaft *b* when the latter is rotated. The bevel-gear *q* meshes with a corresponding bevel-gear *r* on the spindle *r'* vertically journaled in the frame of the carriage *o*. The spindle *r'* carries at its lower end a pinion *s'* and a crank *s*, which has a grooved guide for a sliding block *t*, which can be radially adjusted in the said guide, *i. e.* in the crank *s*, and held by means of a screw *t'*, so that the crank-pin *t*, which has a spherical end *u*, can obtain various effective lengths of crank. Mounted on the end *u* of the crank-pin is the grinding or polishing head *v*, which carries a detachable flanged holder *v'* for receiving the grinding or polishing pad, the latter not being shown. Close to the spindle *r'* is an auxiliary spindle *w'* which carries at its lower end a pinion *w* having the same number of teeth as the pinion *s'* and being rotated at equal speed therewith by means of an intermediate gear *x*. Further, the lower end of the shaft *w'* carries a crank *y*, likewise having a guide for a radially displaceable slide *y'*, which is adjustable conformably with the slide *t* of the crank *s* and can be fixed by means of a screw *z'*. The slide *y'* has a crank-pin *z* which enters into a projection *z'* on the head *v*.

When the shaft *b* rotates, both the cranks *s* and *y* rotate while remaining parallel to each other, and drive the grinding or polishing head *v* without preventing it from tilting about the crank-pin *u*. Further, fastened to the framework of the carriage *o* is a sleeve 12 having a female thread engaging with the screwed spindle *c*, whereby the carriage *o* and the grinding or polishing head thereon are propelled over the workpiece in one direction or the other according to the direction of the rotation of the spindle *c*. When the belt-pulley *k'* is also driven the head *v* is also rapidly driven to-and-fro. The work-table 13 is slideable in guides 14 transversely of the direction of motion of the head *v* and can also be raised and lowered by known devices in order to press it against the head with a suitably light or heavy pressure according to requirements. In the embodiment the frame 15 (Fig. 3) is guided vertically in the end walls at 16 and rests on the antifriction rollers 17 at the ends of two-armed levers 18

which are fulcrumed at 19 in the front and rear frames *m*, *m'*. The adjacent ends of the levers 18 are traversed by a rod 20 (Fig. 3), whose ends are guided vertically in the frames *m*, *m'*. One end of this rod carries a slotted rack 21 which is guided in the frame *m*. Meshing with this rack is a pinion 22 on a small shaft 23 journaled in the frame *m* and carrying at its outer end a hand-wheel 24. The inside arms of the levers 18 carry weights 25 which more than counterbalance the weight of the work-table 13, whereby they always tend to move the table upward with a slight pressure in order as much as possible to assist the workman tending the machine. The table 13 can therefore be moved up and down by the hand-wheel 24 as desired.

I claim:

1. In a grinding and polishing machine of the character described, the combination of a frame, a vertical crank mounted therein, a grinding or polishing head connected to said crank by a ball-and-socket joint; means for preventing said head from rotating about the vertical axis of said ball-and-socket joint while allowing it to oscillate about any horizontal axis thereof, means for rotating said crank, and means for slowly moving the axis of said crank horizontally and means for imparting to the crank a rapid horizontal reciprocatory movement.

2. In a grinding and polishing machine of the character described, the combination of a frame, two vertical parallel cranks mounted therein, a grinding or polishing head connected to one crank by a ball-and-socket joint and only vertically slidably connected with the other crank, means for rotating said cranks at equal speeds, and means for slowly moving the axes of said cranks horizontally and means for imparting to the crank a rapid horizontal reciprocatory movement.

3. In a grinding and polishing machine of the character described, the combination of a frame, a vertical crank mounted therein, a grinding or polishing head connected to said crank by a ball-and-socket joint, means for rotating said crank, and means for slowly moving the axis of said crank horizontally, and means for imparting to the crank a rapid horizontal reciprocatory movement.

4. In a grinding and polishing machine of the character described, the combination of a frame, a vertical crank mounted therein, a grinding or polishing head connected to said crank by a ball-and-socket joint, means for preventing said head from rotating about the vertical axis of said ball-and-socket joint while allowing it to oscillate about any horizontal axis thereof, means for rotating said crank, and means for

slowly moving the axis of said crank horizontally; a horizontal feed-shaft operatively connected with said crank and mounted rotatably and axially displaceably in said frame, and means for longitudinally reciprocating said feed-shaft.

5. In a grinding and polishing machine of the character described, the combination of a frame, a vertical crank mounted therein, a grinding or polishing head connected to said crank by a ball-and-socket joint, means for preventing said head from rotating about the vertical axis of said ball-and-socket joint while allowing it to oscillate about any horizontal axis thereof, means for rotating said crank, and means for slowly moving the axis of said crank hori-

zontally; a horizontal feed-shaft operatively connected with said crank and mounted rotatably and axially displaceably in said frame, and means for longitudinally reciprocating said feed-shaft; an auxiliary shaft journaled in the frame and having right and left handed threads which cross and join at their ends, two stops fast on said feed-shaft, 25 and a block engaging said threads and embracing said feed-shaft between said stops.

In testimony whereof, I affix my signature in the presence of two witnesses.

RUDOLF OCHSCHIM.
